UNITED STATES PATENT OFFICE.

GEORGE F. RAUCH, OF PUKWANA, SOUTH DAKOTA.

SAFETY CRANK FOR AUTOMOBILES.

Application filed October 27, 1921. Serial No. 510,787.

To all whom it may concern:

Be it known that I, GEORGE F. RAUCH, a citizen of the United States, residing at Pukwana, in the county of Brule and State 5 of South Dakota, have invented certain new and useful Improvements in Safety Cranks for Automobiles; and I do declare the following to be a full, clear, and exact description of the invention, such as will enable 10 others skilled in the art to which it appertains to make and use the same.

This invention relates to an improved safety crank for automobiles, and it has for its principal object to devise a novel device of 15 this class which will overcome the possibility of the operator being injured in case the engine backfires, this being due to the fact that the improved crank is instantaneously disengaged from the shaft as soon as the 20 shaft starts to rotate in a reverse direction.

Another object of the invention is to generally improve upon cranks of this class by the provision of one of extreme simplicity and durability which can be substituted for 25 the usual type of crank by simply cutting off a portion of said crank.

Other objects and advantages of the invention will be apparent during the course of the following description.

30 In the accompanying drawing forming a part of this specification and in which like numerals are employed to designate like parts throughout the same:

Figure 1 is a side elevational view of a 35 crank constructed in accordance with this invention.

Figure 2 is a central vertical sectional view through the hollow arm and ratchet.

Figure 3 is a sectional view, with parts in 40 elevation taken at right angles to Fig. 2.

Figure 4 is a top plan view of Fig. 1.

In carrying out the invention, I make use of an attaching member which is generally designated by the numeral 1, the same including a portion 2 having a socket formed 45 therein into which one end of the old crank C is designed to extend. It may be conveniently stated here that in order to apply my improved crank, I simply cut off the 50 downturned portion of the old hand crank and extend the remaining horizontal part of the latter into the socket and secure it to the portion 2 in any suitable way. Member 1 in addition to embodying this socketed portion includes a stub axle 3 on which a ratchet disk 4 is rigidly secured. The fork-arms 5

of a hollow arm 6 are loosely mounted on the axle 3 and are positioned on opposite sides of the ratchet disk 4. Inasmuch as the outer end of the axle is screw-threaded, 60 a nut 7 is placed thereon and serves to hold the arm 6 in place. The device in addition to embodying the parts so far described includes what may be conveniently termed a retractile hand-grip 8 which is arranged at 65 right angles to the arm 6 and is designed to be grasped in order to permit the device to be actuated in the usual way for rotating the crank shaft. At its inner end, the hand-grip is formed with a flattened head 9 which is 70 pivoted between spaced ears 10 at the outer end of the arm 6. This head is pivoted to a pawl 11 which is of considerable length and extends slidably through the bore of 75 the arm 6. By examining Fig. 2 it will be seen that the inner end of this pawl is beveled as indicated at 12 and is designed to engage the teeth of the ratchet disk 4 so as to couple the arm and hand-grip with the 80 attaching member 1 to permit these parts to move as a unit. Coiled springs 14 are arranged in the bore of the arm 6 and surround the pawl 11 to normally hold the latter out of engagement with the ratchet 85 disk.

In use, the hand-grip 8 is grasped in the usual way and a slight outward push is exerted thereon to force and hold the pawl in engagement with the teeth of the ratchet disk. Consequently, when the device is rotated, rotary movement will be imparted to the crank-shaft to start the engine. In case 90 the latter backfires, the operator quickly releases the hand-grip and the spring 14 automatically disengages the pawl from the 95 teeth of the ratchet and the attaching member 1 is permitted to rotate, yet does not effect a movement of the arm 6. It therefore follows that with such an arrangement, the operator is protected against injury. 100

By carefully considering the description in connection with the drawing, persons familiar with devices of this class will doubtless be able to obtain a clear understanding of the invention. Therefore, a more lengthy 105 and detailed description of the invention is deemed unnecessary.

Since probably the best results may be obtained with the construction and arrangement herein shown and described, this is 110 taken as the preferred embodiment of the invention. However, I wish it to be under-

stood that minor changes coming within the scope of the invention as claimed may be resorted to if desired.

I claim:

- 5 1. A safety crank for automobiles comprising a ratchet member adapted to be fixedly connected with a part of the existing crank shaft, and a hand operated crank including an arm loosely mounted around 10 said ratchet member, a hand grip pivotally mounted at an intermediate point thereof to said arm, and a pawl associated with said crank and cooperable with said ratchet, said pawl being pivotally connected to one free 15 end of and controlled by said hand grip.
2. A safety crank for automobiles comprising an attaching device, a ratchet rigidly secured to said device, a tubular arm loosely mounted at one end on said device and provided with a pair of offset ears at the free 20 end thereof, a laterally disposed hand-grip pivotally mounted between said ears and having one end thereof project over the tubular arm, and a spring pressed pawl 25 slidably arranged in the bars of said arm.

and engaged with the teeth of said ratchet, said pawl being pivotally connected with the end of said hand grip projecting over said arm.

3. A safety crank for automobiles comprising an attaching member including a portion having a socket, also including an axle, a ratchet disk rigidly secured on said axle, a hollow arm rotatably connected with said axle, said arm being movable with respect to said member, a pawl slidably arranged in the bore of said arm and being adapted for co-operation with said ratchet, a spring associated with said pawl for automatically disengaging the latter from said ratchet, and an angularly disposed hand-grip pivotally connected with the outer end of said hollow arm, said hand grip being also pivotally connected with the adjacent end of said pawl for imparting sliding movement to the latter.

In testimony whereof I have hereunto set my hand.

GEORGE F. RAUCH.
